United States Patent Office

Des. 183,967
Patented Nov. 25, 1958

183,967

MATTRESS

William T. Harris, Missoula, Mont.

Application November 7, 1955, Serial No. 38,769

Term of patent 7 years

(Cl. D5—2)

Fig. 1

Fig. 2

Figure 1 is a perspective view of the mattress embodying my new design.

Figure 2 is a side elevational view thereof.

The side opposite that shown in Figure 1 is of substantially the same configuration as that shown.

I claim:

The ornamental design for a mattress, as shown and described.
